UNITED STATES PATENT OFFICE.

WILLIAM A. MYERS, OF RIVERSIDE, CALIFORNIA, ASSIGNOR OF ONE-HALF TO
WALTER E. MYERS, OF INGLEWOOD, CALIFORNIA.

RIBBON MEASURING AND RECORDING DEVICE.

Application filed July 5, 1924. Serial No. 724,870.

To all whom it may concern:

Be it known that I, WILLIAM A. MYERS, a citizen of the United States, residing at Riverside, in the county of Riverside and State of California, have invented new and useful Improvements in Ribbon Measuring and Recording Devices, of which the following is a specification.

This invention relates to the dispensing or 10 withdrawing of ribbons, laces, and the like, from spools.

It is a common practice to wind ribbons and laces upon spools in such a manner that a layer of paper is disposed between the adjacent layers of ribbon or lace, as the case 15 may be, upon the spool.

It is an object of this invention to provide means associated with this paper for indicating the amount withdrawn from the 20 spool.

Another object of this invention is to provide the paper disposed between the layers of ribbon with tabs bearing suitable indicia for indicating a half yard, a yard, 25 and similar distances, from the free end of the ribbon.

A still further object of this invention is to provide a spool of ribbon wherein the ribbon is held away from adjacent ribbon 30 by means of paper which is provided with tabs bendable over the ribbon and which tabs are adapted to be cut in half when cutting off a yard or a half yard of ribbon, and with indicia so arranged upon the tabs that the portion of the tab which remains with the ribbon on the spool will indicate how much ribbon still remains upon the spool.

With these and other objects in view which will be made manifest in the following detailed description and pointed out in the appended claims, reference is had to the accompanying drawings for illustration of the preferred embodiment of the invention, wherein:

Figure 1 is a partial perspective of a portion of the paper adapted to be wound with the ribbon upon the spool.

Fig. 2 is a partial perspective of the paper shown in Fig. 1 and with the ribbon superposed thereon and the tab bent over the ribbon.

Fig. 3 is a perspective showing a spool of ribbon to which my invention has been applied, the first half yard of the ribbon having been removed,

Fig. 4 is a partial perspective of the ribbon upon the paper after the first half yard has been cut off, the remaining portion of the tab shown as being bent back to indicate how much ribbon still remains upon the 60 spool, and

Fig. 5 is a plan view illustrating the paper and ribbon which is placed thereon before winding upon the spool.

Reference being had to the drawings 65 wherein similar reference characters designate similar parts, I have shown a length of ribbon R, which for illustrative purposes is four yards long. The length of ribbon R is superposed upon a length of paper P, 70 also four yards long, and which is somewhat wider than the ribbon R. Arranged along one side of the length of paper P are shown seven tabs 10. The ribbon R is placed upon the paper P, and both are 75 wound upon a spool S by first attaching the end 11 thereto.

As the paper and ribbon are wound upon the spool S, the tabs 10 are turned inwardly over the ribbon R, as shown in Fig. 2. The 80 tabs 10 are provided with a medial line 12 which is to accurately indicate the ends of a half yard of ribbon. Suitable indicia 13, such as "1/2 yd.", are disposed towards the free end of the ribbon from the medial line 85 12, and on the obverse side of the tab 10, as shown in Fig. 2. These indicia indicate that one-half yard of ribbon has been withdrawn from the spool S, and that by cutting across the ribbon and paper opposite the line 12, 90 exactly one-half yard will be given to the customer. On the reverse side of the tab 10, as shown in Fig. 2, and disposed oppositely from the medial line 12, is printed "3 1/2 yd." 95 in this case. As shown in Figs. 3 and 4, the ribbon R may be withdrawn from the spool S and one-half yard may be accurately cut off by cutting on the line 12. Furthermore, the amount of ribbon which remains upon the spool S may be instantly determined by 100 folding back the portion 10^a of the tab 10 and reading "3 1/2 yd." in this case where one-half yard has been removed from a four yard stretch of ribbon originally wound upon the spool.

This feature of the device is especially advantageous in that upon taking inventory, the exact amount upon the spool can be determined without removing the ribbon therefrom. Also when a piece of ribbon of con- 110

siderable length is desired, the clerk in a store can immediately tell whether the amount of ribbon on a spool is of the required length or not.

- 5 6 It is to be understood that the next succeeding tab from the first half yard tab has printed thereon on the side of its medial line 12 toward the free end of the ribbon "1 yd." and upon its reverse side of the portion 10²
- 10 10 "3 yd.", also that the following tab will have printed on it in the same locations "1½ yd." and "2½ yd." respectively.

15 It is seen that I have provided means whereby ribbons or laces may be withdrawn from a spool and suitable lengths determined without the application of the ribbon to a measuring device or a yard stick. Furthermore, it will be seen that I have provided means at the free end of the paper bearing the ribbon from which a portion has been cut for immediately indicating the quantity of ribbon remaining upon the spool.

20 20 It is to be understood that various changes may be made in the detail of construction without departing from the scope of the invention as defined in the appended claims.

I claim:

- 25 30 1. In combination with a spool of ribbon or the like, paper disposed between the layers of said ribbon, tabs arranged along one lateral edge of said paper, and indicia

on said tabs for indicating the amount of ribbon withdrawn from said spool.

2. In combination with a spool of ribbon or the like, paper disposed between the 35 layers of said ribbon, tabs arranged along one lateral edge of said paper, and indicia on said tabs for indicating the amount of ribbon withdrawn from said spool and the amount remaining thereon.

40 3. In combination with a spool of ribbon or the like, paper disposed between the layers of said ribbon, and tabs arranged along one lateral edge of said paper and foldable over the superposed ribbon, said 45 tabs bearing indicia upon the obverse and reverse faces.

4. In combination with a spool of ribbon or the like, paper disposed between the layers of the ribbon, and tabs arranged 50 along one lateral edge of said paper and foldable over the superposed ribbon, said tabs having indicia upon their obverse and reverse faces, the indicia on one face indicating the amount of ribbon and paper withdrawn from the spool and the indicia on the other face indicating the amount remaining on the spool.

55 In testimony whereof I have signed my name to this specification.

WILLIAM A. MYERS.
